Deane atte

United States Patent Office.

ROYAL E. DEANE, OF BROOKLYN, NEW YORK.

Letters Patent No. 97,766, dated December 14, 1869.

WATER-HEATER FOR CULINARY PURPOSES.

The Schedule referred to in these Letters Patent and making part of the same.

To all whom it may concern:

Be it known that I, ROYAL E. DEANE, of Brooklyn, in the county of Kings, and State of New York, have invented a new and useful Water-Heater for Culinary Purposes; and that the following is a full, clear, and correct description of the same, reference being had to the accompanying drawings, making part of this specification, and to the letters of reference marked thereon, in which—

Figure 1 is a side elevation of my improved water-heater.

Figure 2 is a sectional view of the same.

Figure 3 is a top view of the same, a portion of the cover being removed.

Figure 4, a view of the measuring-scale placed upon the side of the vessel.

In the drawings, like parts of the invention are designated by the same letters of reference.

The nature of the present invention consists in the construction of an improved water-heater for culinary purposes, as more fully hereinafter set forth, the object of the invention being to utilize the steam, formed by boiling the water contained in the vessel, so that a supply of boiling water may be forced from the heater into a contiguous vessel, or drawn from it when desired.

To enable those skilled in the art to make and use my invention, I will describe its construction and operation.

A is a cylinder, formed of copper or any suitable metal, which cylinder is closed at its lower end, and is provided with a cover, B, secured tightly upon its top or upper end, so that the cylinder A shall be steam-tight.

The cylinder A has an opening cut in it, which opening extends very nearly from the bottom to the top of the same, and is closed with a plate of glass, or any transparent material, C.

This opening is generally made in the side of the cylinder, and upon one side of this opening is placed a scale, D, (see fig. 4,) numbered from one (1) upward to any extent, according to the size of the cylinder, and showing, as more fully hereinafter described, the number of pints or quarts that may pass from the cylinder into any vessel with which the same may be connected.

E shows a funnel, inserted in the top B, and communicating with a pipe, F, which pipe extends very nearly to the bottom of the cylinder A.

In one side of the funnel is inserted a pipe, G, made to communicate with a second vessel, into which it may be desired to transfer boiling water from the cylinder A.

In the top of the cylinder is inserted a steam-cock, H; and

I is a pipe connecting the cylinder A with a water-pipe or reservoir.

J shows a cock or faucet inserted in the lower end of the cylinder A, for drawing off, when necessary, boiling water from the heater, which cock or faucet is connected to a bent pipe, K, communicating with the interior of the cylinder A.

L is a plate or disk, of metal, secured within the cylinder a short distance below the cover B, and about on a line with the pipe I, which plate or disk of metal is perforated, so that any water introduced through the pipe I may pass through the perforations into the cylinder A.

Such being the construction, the operation may be thus described:

The heater A is filled with water by opening the cock H, to allow the air to escape, and pouring water into the same through the funnel E, or through the pipe I, connected, as already stated, with a water-pipe or reservoir.

If the water be poured into the funnel E, it enters the cylinder, through the pipe F; and if supplied through the pipe I, it passes through the perforated plate or disk of metal.

If the cylinder has been filled to the height of the scale D, the cock H is closed, and the heater is placed over a fire or over steam-pipes.

As soon as the water contained in the cylinder boils, and steam is formed, this steam acts upon the boiling water, forcing the same up through the pipe F, and into and through the pipe G into a secondary vessel, used for making coffee, tea, or for any desired culinary purpose; or a supply of boiling water may be drawn from the heater through the cock or faucet J, so long as the steam will force the boiling water through the bent pipe K.

When at any time it may be deemed advisable, so to speak, to "cool off" the water and steam contained in the cylinder A, a supply of cold water may be introduced into the same through the pipe I, which water will pass into the interior of the cylinder A, through the perforated disk or plate of metal L, and be showered, as it were, upon the boiling water, serving to condense the steam contained therein.

The scale D, as the water falls in the cylinder, serves to indicate the exact quantity of boiling water which has passed off, or been drawn from the heater.

The steam-cock H, when opened, allows the escape of steam at any time.

The value of the present invention will be found to consist in the fact that the steam formed by the water boiling in the vessel is utilized, and made to force a body of boiling water into a vessel contiguous to the heater, and that the person using the heater may feel assured that only boiling water has been so forced into

the contiguous vessel connected with the heater, and by consulting the scale, can determine the exact quantity which has been consumed, and that the steam will also force boiling water through the pipe K, to supply the faucet I.

This feature, when the heater is connected with a coffee or tea-urn, will be found advantageous, while the arrangement for condensing the steam at any time is a second advantage.

While I have shown the pipe F as placed within the cylinder A, I am well aware that this pipe F will accomplish the same result if placed outside the cylinder A, and allowed to enter the bottom or sides of the cylinder A. In this case, the pipe G would be connected with the pipe F, at or near its upper end.

Having thus described my present invention,

What I claim as new, and desire to secure by Letters Patent, is—

1. So constructing a water-heater for culinary purposes, that the steam rising from the water boiling in

the heater, shall force any desired quantity of boiling water out of said heater and into a contiguous vessel, properly connected with the heater, when the same shall be constructed substantially as described.

2. The combination, with a steam-tight cylinder, A, of the pipes F and G, when the same shall be constructed and operate substantially as and for the purposes set forth.

3. In combination with the subject-matter of the second clause of claims, the steam-cock H, pipe I, and perforated plate or disk L, constructed and operating as and for the purposes specified.

4. The combination, with a steam-tight cylinder, A, provided with the pipes F and G, of a measuring-scale, D, as and for the purposes fully described.

ROYAL E. DEANE.
